UNITED STATES PATENT OFFICE.

RALPH E. PIERCE, OF ZION, ILLINOIS.

RAILWAY-CROSSING-GATE SIGNAL.

1,426,839.

Specification of Letters Patent. Patented Aug. 22, 1922.

Application filed February 17, 1922. Serial No. 537,169.

To all whom it may concern:

Be it known that I, RALPH E. PIERCE, a citizen of the United States of America, and a resident of Zion, in the county of Lake 5 and State of Illinois, have invented a certain new and useful improvement in Railway-Crossing-Gate Signals, of which the following is a specification.

This invention relates to an illuminated 10 signal attachment for railway grade crossing gates of the swinging arm type, and has for its object:

To provide a structural formation and association of parts and mechanisms where- 15 by an automatic shifting or turning of a signal lamp from a highway signalling position to railway track signalling position and vice versa, is effectively attained by the upward and the downward swinging move- 20 ment of the gate arm carrying the signal lamp, all as will hereinafter more fully appear.

In the accompanying drawing:-

Fig. 1 is a perspective view illustrating 25 in full lines the signalling appliance in a lowered position displaying a light signal in the direction of the highway, and in dotted lines the appliance in a raised position displaying the light signal direction of the 30 railway tracks.

Fig. 2, is a detail side elevation of the appliance in its raised position.

Fig. 3, is a detail section of the sliding connection between the pendant link and the 35 suspension link of the appliance.

Like reference numerals indicate like parts in the different views.

Referring to the drawing, 1 designates a portion of one of the vertically swinging 40 pair of arms of an ordinary safety gate for railway crossings, carrying near its free end a fixed lateral stem or shaft 2, the free end of which carries a crank arm 3 as shown.

4 designates a pendant link journalled at 45 its upper end on the shaft 3 aforesaid, and having at its lower end a lateral flange 5 formed with a guide slot 6 for the purpose hereinafter stated.

7 designates a spirally formed suspen- 50 sion link, the spiral 8 of which is formed midway the length thereof and preferably with a quarter twist as shown. At its upper end the suspension link 7 is connected to the free end of the crank arm 3, prefer- 55 ably in a resilient manner and by means of an interposed spiral spring 9, while at

its lower end said link is provided with a snap hook 10, or other like means for detachable holding engagement and support of the handle or bail of a signal lantern 11, 60 which as used in the present improvement is of the ordinary double lens type shown.

In an assembled condition of the parts, the suspension link 7 passes through the slot 6 of the pendant link 4 and has move- 65 ment therein, and the operation of the mechanism is as follows:-

With the gate arm 1 in the vertical position shown in dotted lines in Fig. 1, and in full lines in Fig. 2, the spiral portion 8 70 of the suspension link 7 is at a point above the guide slot 6 of the pendant link 4, with the lenses of the signal lantern 11 pointing in the direction of the railway tracks with a descent of the gate arm to a horizontal po- 75 sition across the highway, the spiral portion 8 of the link 7 is gradually drawn through the slot 6 of the pendant link 4 by the weight of the lantern 11 and accesso- 80 ries, in that the free end of the crank arm 3 moves towards the point of engagement of the link 7 and slot 6 of the link 4, and so that as said crank arm nears a horizontal plane, the spiral portion 8 of the link 7 will reach a position below the lateral flange 5 85 of the link 4 and in so doing will impart a quarter revolution to said suspension link 7 and lantern 11, bringing the lenses of said lantern in the direction of the highway to give a visible indication of danger to 90 passing persons and vehicles.

12 designates a casing or housing secured to the pendant link 4 and adapted to enclose the mechanism from the weather, etc.

Having thus fully described my invention, what I claim as new and desire to secure by Letters Patent, is:-

1. In a signal appliance of the type described, the combination of a vertically swinging gate arm, a suspension link pivotally connected to said arm and provided at its lower end with means for supporting a signal lantern, a pendant link pivotally connected to the gate arm at a point removed from the connection of the suspension link, and an operative connection between said links for imparting a turning movement to the suspension link in unison with the movement of the gate arm. 100

2. In a signal appliance of the type de- 110 scribed, the combination of a vertically swinging gate arm, a suspension link pivot-

ally connected to said arm by an intermediate spring and provided at its lower end with means for supporting a signal lantern, a pendant link pivotally connected to the gate arm at a point removed from the connection of the suspension link, and an operative connection between said links for imparting a turning movement to the suspension link in unison with the movement of the gate arm.

3. In a signal appliance of the type described, the combination of a vertically swinging gate arm, a crank member fixedly attached to said arm, a suspension link connected to one end of the crank member and having a spiral formation intermediate its length and means at its lower end for the support of a signal lantern, a pendant link pivoted to the other end of said crank member and having at one end a slot for operative engagement with the spiral formation of the suspension link to impart a turning

movement to the suspension link and lantern in unison with the movement of the gate arm.

4. In a signal appliance of the type described the combination of a vertically swinging gate arm, a crank member fixedly attached to said arm, a suspension link connected to one end of the crank member by an intermediate spring and having a spiral formation intermediate its length and means at its lower end for the support of a signal lantern, a pendant link pivoted to the other end of said crank member and having at one end a slot for operative engagement with the spiral formation of the suspension link to impart a turning movement to the suspension link and lantern in unison with the movement of the gate arm.

Signed at Chicago, Illinois, this 16th day of February, A. D. 1922.

RALPH E. PIERCE.
